UNITED STATES PATENT OFFICE.

MOTOTERU KONDO, OF LOS ANGELES, CALIFORNIA.

COIN-COUNTING DEVICE.

1,362,803.

Specification of Letters Patent.

Patented Dec. 21, 1920.

Application filed February 10, 1920. Serial No. 357,539.

To all whom it may concern:

Be it known that I, MOTOTERU KONDO, a subject of the Emperor of Japan, residing in the city and county of Los Angeles, 5 State of California, have invented a new and useful Coin-Counting Device, of which the following is a specification.

This invention relates to an improved device for counting coins, and its objects are 10 to provide a manually reciprocable and relatively shallow hopper having a series of obstructions arranged on the bottom thereof to intercept the free movement of the coins whereby the coins will arrange themselves 15 in a regular order for counting, or sorting the same, in substantially regular multiples of dollars or fractions thereof, in accordance with the value of the coins.

Other objects are to provide a device of 20 this character which is durable, simple in construction, and easily manipulated for sorting or counting coins.

Other objects and advantages may appear in the subjoined detail description.

Upon the annexed drawings, Figure 1 is 25 a plan view of my device showing the receptacles as arranged for the smaller coins. Fig. 2 is a plan view of the reverse side of the device. Fig. 3 is an enlarged and sectional view showing the fabric cover in position for counting and distributing the coin within the coin receptacles. Fig. 4 is a transverse and enlarged sectional view showing the details of the adjustable gage. Fig. 30 5 is a fragmentary and perspective view showing the door which normally closes the delivery chute.

Referring to the drawings, the coin counting device embodying my invention consists 40 of a casing 11, forming the oppositely disposed hoppers 12, and provided with a handle 13, the grooved flanges 14, having the longitudinal grooves 15, and provided with the end stop flange 16, curved on the inner 45 side 17, to fit approximately the periphery of the coins. A series of obstructions 18, are disposed on the bottom 19, of the smaller coin hopper 20, and on the opposite side, a series of obstructions 20, are disposed on the bottom 21, of the larger coin hopper 12. These obstructions are approximately of 50 less height than the thickness of the coins so that when the receptacles 22, or 23, are filled each with a coin, the remaining coins 55 will readily slide over the intercepted coins, and may be removed by turning back the

fabric cover 24 and tilting the device at a suitable angle and further brushing off the extra coins with the hand or a brush. A sliding gage 25, is in engagement with the 60 grooves 15, and is provided with plungers 26, adapted to engage with the notches 27 disposed at intervals in the bottom of the grooves 15. The plungers 26 are normally maintained in engagement by the springs 65 28, interposed between the shoulders 29, of the plungers, and stops 30. Lugs 31 are provided for manipulating the plungers 26, to adjust the gages. The side flanges are provided with a series of characters 32, so 70 that the sliding gages may be set at the desired position. The fabric cover is provided with loose connections 33, consisting of rings in engagement with the bar 34 and with loops 35 on the end of the casing. The cover 75 is further provided with a bail 36, which is grasped by the thumb while the device is shaken or agitated to distribute the coins within the receptacles. The delivery chutes 37, for either hopper, are normally closed 80 by the member 38, secured to the spring latch 39, pivotally connected by pivot member 40, to the casing. The latch member 39 is provided with a projection 41, fitting, in the closed position, a corresponding de- 85 pression in the casing.

In use, a number of coins are placed loosely within the receptacle hopper best adapted for the size of the coin, the fabric cover is placed in position, and the device 90 is actuated with a reciprocating movement, which will cause the coins to assume a flat-wise position within the receptacles. The cover is then turned back and the surplus coins may be brushed off with the hand. 95 The cover is then replaced in position, and the device is tilted to a substantially vertical position with the chute corner in the lower-most position, which will cause the coins to arrange themselves in a stack adjacent to 100 the door 38, which may swing to the open position for either chute, leaving an exit space for the stack of coins. After delivery of the coins, the operation is repeated for another pile of coins.

From the foregoing description it may be seen that I have provided a simple and efficient device for counting coins, and arranging them in stacks containing predetermined sums for wrapping, in accordance 110 with the system of counting employed in banks and stores.

What is claimed is:

1. In a coin-counting device, the combination with a casing arranged to form two oppositely disposed hoppers and a handle 5 for the casing, of a fabric cover adapted to inclose either hopper, a series of obstructions arranged to intercept the free passage of coins upon the bottom of the hoppers, a delivery chute arranged at the end of the 10 casing to stack the coins, and a closing member for the delivery chute.

2. In a coin-counting device, the combination with a casing embodying a bottom member, flanges extending on either side 15 thereof to form hoppers, and a handle for the casing, of coin obstructing means forming single coin receptacles within either hopper, a cover arranged to cover either hopper, an end flange forming a stacking 20 and delivery chute, and a spring actuated closing member for the delivery chute.

3. In a coin-counting device, the combination with a casing embodying a bottom member, flanges forming therewith oppositely disposed hoppers, and a handle for 25 the casing, of a series of obstructions arranged upon the bottom member and forming a series of single coin receptacles to cause the coins to assume a flat-wise position, a flexible cover for the hoppers, a finger bail for the cover adapted to extend over the handle in the closed position of the cover, a stacking and delivery chute at the 30 end of the hoppers, and a pivotally mounted and spring actuated closure member for the 35 chutes.

4. In a coin-counting device, the combination with a casing embodying a bottom member, flanges forming therewith oppositely disposed hoppers, and a handle for 40

the casing, of obstruction elements disposed upon the bottoms of the hoppers, and projecting approximately the thickness of a coin, a delivery chute at the end of the casing, a concave face on the chute serving to 45 stack the coins, and a spring-actuated closure member normally closing the chutes.

5. In a coin-counting device, the combination with a casing having an end flange, and grooved side flanges forming coin hoppers on opposite sides thereof, of obstruction elements disposed on the bottoms of the hoppers, and projecting slightly less than the thickness of the coins, said elements forming square single-coin receptacles, of gage members extending transversely within the hoppers and engaging with said grooves, plungers sliding in the ends of the gage members and adapted to engage with notches in the bottom of the 50 grooves, springs to actuate the plungers, lugs on the plungers for manipulating the same to release the gage members, a delivery chute at the end of each hopper, a closure member normally closing both 55 chutes, and a fabric cover adapted to close either hopper.

6. In a coin-counting device, the combination with a casing forming oppositely disposed hoppers, of a slideable gage member to vary the capacity of the hoppers, obstruction elements projecting from the bottom of the hoppers approximately less than the thickness of a coin, and forming a series 70 of single-coin receptacles, and a flexible fabric cover secured to the end of the casing and adapted to close either hopper.

In testimony whereof I hereunto affix my signature, this 31st day of January, 1920.

MOTOTERU KONDO.
